SOLITAIRE GAME BOARD

Stanley C. Stockton and Mary J. Stockton, both of 108
Cartwell Drive, Apt. 201, Virginia Beach, Va. 23452

Filed May 19, 1975, Ser. No. 577,057

Term of patent 14 years

Int. Cl. D21—01

U.S. Cl. D34—13 A

FIG. -1

FIG. -2

FIG. -3

FIG. -4

FIG. 1 is a sectional view taken along the lines of 1—1 in FIG. 2 of a solitaire game board showing our new design; and

FIG. 2 is a top plane view thereof; and

FIG. 3 is a sectional view taken along the line of 3—3 in FIG. 2; and

FIG. 4 is a sectional view taken along the lines 4—4 in FIG. 2.

We claim:

The ornamental design for a solitaire game board, as shown.
